HEAT EXCHANGING APPARATUS

Filed May 16, 1928

UNITED STATES PATENT OFFICE

JAMES M. HARRISON, OF CLEVELAND, OHIO

HEAT-EXCHANGING APPARATUS

Application filed May 16, 1928. Serial No. 278,199.

This invention relates to heat exchanging devices and more particularly to constructions adapted for use either in direct or indirect radiation systems.

5 It is one of the objects of the invention to provide a heat exchanging unit that may be built up largely from sheet steel and in such a manner that the cost of manufacture will be lower than that of corresponding units 10 heretofore used and which will be also adapted for manufacture in various sizes by assembling varying numbers of similar elements.

In the accompanying drawings I have illustrated 15 a heat exchanging unit embodying my invention. In these drawings Fig. 1 is a side elevation with certain parts broken away and other parts shown in section.

Fig. 2 is a fragmentary plan view with one 20 of the elements shown in section on the line 2-2 of Fig. 1.

Fig. 3 is a view of the parts shown in Fig. 1, as seen from the left of Fig. 1; and

Fig. 4 is a perspective view of the section. 25 Referring to the drawings, 10 indicates a series of heat exchanging elements that are similar in construction and size and adapted to be assembled in parallel relation to form a complete heat exchanging unit. Each of 30 the elements 10 is made from sheet metal, and preferably of steel, and, where the elements are not too large, the sides may be formed of a single sheet with a bend 11 along one edge. The three open edges of the element are 35 closed by the insertion of metal strips or bars 12, 13 and 14, these strips or bars being welded in place or secured in any other suitable manner. The ends of the bars 13 and 14 are spaced a short distance away from the bars 12 to pro-

40 vide openings 15 and 16 through which the interior of the elements may communicate with the headers 17 and 18. The different elements may be spaced apart by blocks 19 which are preferably arranged at the corners 45 of the elements, as best shown in Fig. 4, to provide space for air to circulate between the elements. The blocks 19 may be welded in position and the headers 17 and 18 may be of any desired shape but I prefer to make 50 them of circular cross section with one side

cut away to permit the headers to span the openings 15 and 16. The headers are preferably welded to the assembled elements, as indicated at 20, and should also be welded to the spacing blocks 19 so that there will be no 55 leakage from the headers to the space between the various elements.

The elements are preferably made thin so as to provide a maximum amount of heat exchanging surface in a given volume and, in practice, I prefer to use bars 12, 13 and 14 that are about $\frac{1}{4}$ " square in cross section and the blocks 19 may be about $\frac{1}{4}$ " wide so as to have a space of $\frac{1}{4}$ " between the different elements. In order to reinforce the sides 60 of the elements to enable them to resist any internal or external pressure, I provide a series of depressions 21 in the sides of the elements, in suitable spaced arrangement, these depressions, in the opposite sides of the 65 elements, being in registration and preferably spot-welded or otherwise secured together.

Heat exchanging units, made up as above described, may comprise any desired number 70 of elements and the headers 17 and 18 will be made the required length depending upon the 75 number of elements assembled into a single unit. The headers of the different units may be secured together by means of the flanges 22 provided thereon and these flanges may 80 also serve as means for connecting the pipes 85 of the system with which the units are connected. It will be understood that the units will be enclosed in a suitable casing but the same has not been shown in the drawings because it forms no part of the present invention.

Having thus described my invention, what I claim is:

1. A heat exchanger comprising a plurality 90 of elements each of which consists of two sheet metal side plates secured together along their edges, spacers between said elements, inlet and discharge headers extending transversely of said elements and welded to the edges 95 thereof, and the edges of the elements having openings into said headers.

2. A heat exchanger comprising a plurality 100 of elements each of which consists of two substantially parallel sheet metal side plates

spaced apart along a plurality of their edges and having filler strips between such edges and secured thereto, spacers between said elements, inlet and discharge headers extending transversely of said elements and welded to the edges thereof and to said spacers, and the edges of the elements having openings into said headers.

3. A heat exchanger comprising a plurality of elements each of which consists of two substantially parallel sheet metal side plates spaced apart along a plurality of their edges and having filler strips between such edges and welded in position, spacers welded in position between said elements adjacent a plurality of corners thereof, inlet and discharge headers extending transversely of said elements and welded to the edges thereof and to said spacers, the edges of said elements having openings into said headers, and the sides of said elements being secured together at spaced points remote from the edges of the sections to reinforce the sections against internal pressure therein.

25 In testimony whereof, I hereunto affix my signature.

JAMES M. HARRISON.
